DESIGN FOR A LAMP SHADE

Rudolph Castro, Los Angeles, Calif.

Application April 16, 1945, Serial No. 119,040

Term of patent 7 years

(Cl. D48—16)

To all whom it may concern:

Be it known that I, Rudolph Castro, a former citizen of Nicaragua, now applying for United States citizenship, residing at Los Angeles, in the county of Los Angeles and State of California, have invented a new, original, and ornamental Design for a Lamp Shade, of which the following is a specification, reference being had to the accompanying drawing, forming a part thereof. Figure 1 is a side perspective view of a lamp shade showing my new design.

I claim:

The ornamental design for a lamp shade, as shown.

RUDOLPH CASTRO.
